UNITED STATES PATENT OFFICE.

J. M. CARR, OF OMAHA CITY, NEBRASKA TERRITORY.

IMPROVEMENT IN SEEDING-MACHINES, &c.

Specification forming part of Letters Patent No. 58,214, dated September 25, 1866.

To all whom it may concern:

Be it known that I, J. M. CARR, of Omaha city, in the county of Douglas and Territory of Nebraska, have invented a new and Improved Combination of a Seeding and Sod-Cutting Machine; and I do hereby declare that the following is a full, clear, and exact description thereof, which will enable others skilled in the art to make and use the same, reference being had to the accompanying drawings, forming a part of this specification, in which—

Figure 1 is a side sectional view of my invention, taken in the line $x x$, Fig. 2; Fig. 2, a plan or top view of the same; Fig. 3, a detached side view of the lower part of a swinging frame pertaining to the same.

Similar letters of reference indicate like parts.

This invention relates to a new and improved combination of a seeding and sod-cutting machine, as hereinafter fully shown and described, whereby seed may be sown and the sod cut and the earth pulverized, so that a fine pliable mold will cover the seed.

A represents a rectangular frame, to the front end of which a draft-pole, B, is attached. This frame is mounted on two wheels, C C, and a spring-bar, D, is attached to its rear end, on which the driver's seat E is secured.

On the front part of the frame A there is secured a seed box or hopper, F, the bottom a of which is of curved form in its transverse section, the convex surface being uppermost, and this bottom a is perforated with oblique slots, b , shown clearly in Fig. 2. Underneath this curved bottom a there is a cylinder, G, perforated with holes c , which serve as seed-cells.

This cylinder G is rotated, as the machine is drawn along, by means of a toothed wheel, H, on the axle d of the wheels C C, gearing into a pinion, e, at one end of said cylinder.

I represents a frame composed of two parallel bars, f f, connected by a transverse rod, g, and having their upper ends connected to the axle d by metal straps h h, which admit of the frame I freely swinging on the axle d without interfering with the free rotation of the axle. The lower ends of the bars f f have each a small wheel, J, attached, the axis of said wheels being secured to plates i having oblong slots j in them, through which slots screws k pass into the bars f f. By this mode

of attachment the wheels J may be adjusted higher or lower, as circumstances may require.

In the lower part of the frame I there is fitted a cylinder, K, having knives or cutters l attached to it in spiral rows, and in such a manner that they may be removed and cutters of different forms applied, as the nature of the work may require. This cylinder K has a pinion, m, on one end of it, into which a wheel, L, on a shaft, n, gears, said shaft being fitted in the frame I, and also having upon it a pinion, o, into which the wheel H on the axle d gears. By means of this gearing the cylinder G will be rotated as the machine is drawn along, and the sods cut and the earth pulverized by the knives or cutters l, the depth of the penetration of the latter being regulated, as circumstances may require, by adjustment of the wheels J J, and the cylinder G, it will be seen, will rise and fall to conform to the irregularities of surface over which it may pass.

The seed is distributed or sown by the rotation of the cylinder G, the seed passing through the slots b in the bottom a of the box or hopper F, and into the cells in cylinder G, from which they drop as the cells pass around underneath the axis of said cylinder. The cylinder G may be raised at any time above the surface of the ground by actuating a lever, A*, on a bar, a*, on the frame A, said lever being connected by a link, b*, with the lower end of frame I.

I do not claim separately the seed-distributing device, for that has been previously used; but

I do claim as new and desire to secure by Letters Patent—

1. The swinging or adjustable frame I, attached to the axle d , as shown, and provided with the cylinder K, having knives or cutters l attached, in combination with a seed-dropping mechanism, all arranged and applied to a mounted frame, substantially as and for the purpose specified.

2. In combination with the above, the adjustable wheels J J, attached to the lower end of the frame I, substantially as and for the purpose set forth.

JAS. M. CARR.
